UNITED STATES PATENT OFFICE.

FRANK K. HOOVER AND ARTHUR J. MASON, OF KANSAS CITY, MISSOURI.

APPARATUS FOR EXCAVATING AND SLUICING GRAVEL OR OTHER MATERIAL.

SPECIFICATION forming part of Letters Patent No. 759,108, dated May 3, 1904.

Application filed March 21, 1898. Serial No. 674,633. (No model.)

To all whom it may concern:

Be it known that we, FRANK K. HOOVER and ARTHUR J. MASON, both citizens of the United States, residing at Kansas City, in the county 5 of Jackson and State of Missouri, have invented certain new and useful Improvements in Apparatus for Excavating and Sluicing Gravel or other Material, of which the following is a specification.

10 Our invention relates to improvements in apparatus for excavating and sluicing gravel and other material, the same having reference more particularly to the raising and sluicing of auriferous sand and gravel from 15 the beds of rivers and streams by means of an apparatus carried on a floating barge, although our improvements are also capable of use in other relations—as, for instance, on docks and piers in raising ore, coal, and like 20 material from the holds of vessels. The apparatus heretofore in use for these purposes have certain characteristics which we desire to avoid. In the chain-and-bucket type the 25 platform or support on which the apparatus is mounted must be substantially rigid and unyielding, and where this platform or support consists of a floating barge or raft the latter must be firmly held by tackle or spuds to resist the digging energy of the buckets as 30 they load. In the dipper-dredge type the same necessity exists, and in all the clam-shell types, as well as the dipper type, it has been necessary to swing the excavator horizontally, so as to effect a dump into a hopper or receptacle 35 where the material may be dealt with as desired. The strains resulting cause a rocking side motion and necessitate a heavy barge of large dimensions. In our invention the resultant of all the lines of action and gravity is substantially over and along the longitudinal center line of the platform or support. Where the support is a floating barge, we are 40 thus enabled to do the work described with a much lighter barge having a minimum draft and of much smaller dimensions, yet so little affected by the shifting loads due to operation as not to interfere with the inclination of the sluices, and consequently their successful op-

eration. The light barge and our system of excavation permit the use of light lines to 50 control the movement of the barge, making it quick and handy in movement.

Inasmuch as the principal application of our invention contemplated by us is in the raising and transporting of auriferous sand 55 and gravel from the beds of rivers and streams by means of hoisting and sluicing apparatus carried and supported on a floating barge, we have illustrated the platform or support as a barge, and in the following description shall 60 describe our invention in connection with its peculiar and advantageous (but not exclusive) adaptability to a floating barge.

We prefer to use the grab or grapple described in our application for Letters Patent 65 filed March 29, 1897, Serial No. 629,740; but we do not wish to be limited to this form, as our apparatus is adapted to any form of grapple. This form of excavator from its nature communicates to the barge only a vertical strain acting through its point of suspension. It is therefore not necessary in our invention to provide for resisting the digging energy of the excavators either by spuds or by the lines attached to anchors for moving 70 the barge. The grab in loading is always in the same relative position to the end of the barge. As we provide for the certain and constant movement of the barge and can secure a different location from which each successive load is taken, we are able to be certain 75 of the systematic cleaning of bed-rock in auriferous placer-mining.

Another object of our invention is to enhance the speed in operation. We therefore 85 provide mechanism by means of which the excavator is closed, raised to the desired height, and moved rearwardly by the single continued action of the engine. At the same time we bring to a minimum the distance the 90 excavator must travel to move the material from its natural position to a point above the hopper or other receptacle where it may be treated as desired. Likewise as the movement is direct and the excavator is close to the 95 boom at the time of lateral movement and

dumping lost motion or swing is eliminated, making it feasible and safe to move the boom with great rapidity.

To accomplish the above objects our invention consists of certain features of novelty hereinafter described, and pointed out in the claims.

In the accompanying drawings, Figure I represents a general view in perspective of the apparatus, showing position of boom at which the excavator is raised and lowered. Fig. II represents a like perspective view showing position of boom as it carries the excavator over the hopper. Fig. III represents a detail elevation of the rocker-foot of the boom. Fig. IV represents a detail elevation of the feed-shutters over the hopper. Fig. V represents a detail elevation of the mechanism for moving the barge; and Fig. VI shows in elevation the worms, the worm-gears, and spools used for moving the barge.

Similar numbers refer to similar parts throughout the several views.

1 designates a suitable platform or support, here shown as a floating barge, supporting the whole apparatus and anchored by the lines 2 2^a 2^b. The lines 2, 2^a, and 2^b are connected with suitable stationary objects on the land in the usual manner and inboard passing over the guide-pulleys 25^a 26^a 27^a, respectively, are each wrapped several times around spools 25 26 27 for the purposes hereinafter mentioned.

3 represents a generally upright frame erected at the forward end of the barge and substantially centrally of such end upon which is mounted a hopper 4.

5 represents a sluice communicating with the bottom of the hopper and extending rearwardly longitudinally over the barge and to some distance beyond the stern and provided with the customary appliances for gold-saving. The hopper is provided at or near its top with the horizontal shutters or feed-doors 6, (shown in detail in Fig. IV,) the use of which will appear later. Each of said doors is independent and may be separately and independently operated by a handle 7.

8 represents a pump discharging into the hopper to furnish the water for sluicing.

9 represents a boom provided with a rocker-foot to rock on the deck. As shown in Fig. III, this rocker-foot is prevented from slipping or creeping by the straps 11 and 12, attached at one end to the rocker and at the other end to the deck. At the upper and outer end of the boom are mounted the sheaves 13 and 14 on the head of the boom, carrying, respectively, the opening-lines 15 and the closing-lines 16 to the excavator. Said closing-lines 16 passing over the leading sheaves 17 and the opening-lines 15 passing over the leading sheaves 18, mounted on the frame 3,

are connected with the drum 19 for the opening-lines and 20 for the closing-lines. The 65 said drums are arranged to be operated by the engine 21 by friction-clutches and are provided with brakes. It will be noted that the leading sheaves 17 18 are located between the head of the boom and the drums and are 70 so related in position to the foot of the boom and to the sheaves 13 14 on the head of the boom that the strains along the lines 15 16 almost counterbalance the weight of the boom. This location of the leading sheaves 17 and 18 75 may vary somewhat with the length and weight of the boom and the location of the rocker-foot; but it should be such that the inner angle comprehended between the line from the head of the boom to the leading 80 sheaves and the line from the head of the boom to its point of support shall be slightly greater in all operative positions of the boom than the angle comprehended between this last-named line and the line from the head of 85 the boom to the excavator. The result and advantage of this arrangement is that the pull on the lines to raise the excavator being very little less than the pull required to rock the boom and swing the excavator over the 90 hopper after the excavator has been raised the boom is, as it were, substantially balanced between the lines of force, and consequently there is no appreciable shock when the excavator strikes the boom to begin its 95 inward movement. In practice the sheaves are adjusted to such position that in action the shock or strain on the parts at the moment when the boom is called on to raise is minimized. Upon the lines 15 16 is hung the excavator 23.

24 represents a boiler from which steam is supplied to operate the engine and the pump.

In operation the barge being anchored in the desired location by the lines 2 2^a 2^b to 105 suitable stationary objects the excavator is lowered by the opening-lines 15 to the point in advance of the barge from which the load is to be taken. The power is then transferred to the closing-lines 16. The excavator is closed and the load taken, and by the continued action of the lines 16, which have now become the lifting-lines, the excavator is elevated until the boom is reached, when, as the said lines continue to act, the boom is moved inwardly toward and finally to the position shown in Fig. II, bringing the excavator over the hopper, when it is dumped by releasing the closing-lines and holding the opening-lines. The opening-lines are then paid out by the brake on the drum 19, whereupon the boom moves outwardly and downwardly toward and finally to the position shown in Fig. I. Check-lines 25^b then act to restrain the boom from descending farther. The continued release of the opening-lines causes the excavator 110 115 120 125

to descend open and in a condition to take another load and repeat the operation. It will be observed, further, that the path of the excavator after it is raised to the boom-head in 5 its movement as the boom rocks to bring the excavator over the hopper is along a line in the vertical plane of the boom's movement, which plane is substantially coincident with the longitudinal central vertical plane of the 10 barge. Also it will be seen that by locating and arranging the parts as above set forth the excavator is elevated by drawing in on the closing-lines 16 until the excavator is raised up to and strikes the head of the boom in its 15 outer or lower position, as shown in Fig. I. Then by continued direct pull in the same direction on said closing-lines the boom is rocked, carrying the excavator rearwardly inward in the vertical plane of the upward and 20 inward swing of the boom to and over the hopper, as shown in Fig. I. This action of rocking the boom by the direct continued pull on the excavator-lines to carry the excavator inwardly in the vertical plane of the boom's 25 movement to and over the hopper is so far as we are aware new in the art.

When the load is dumped into the hopper, it is often undesirable that the full amount thereof should be at once admitted to the 30 sluice. The shutters or feed-doors 6 are located horizontally across the mouth of the hopper, being mounted on shafts extending transversely across the same, and are of such number and size as to when closed occupy or 35 fill up the greater part of the mouth of the hopper, but leaving a space between the adjacent doors through which a part of the material will fall, while the doors serve to intercept the bulk of the load. By means of the 40 handle 7 these shutters may be operated so as to admit to the sluice such amounts of material as can be properly acted upon by the water supplied by the pumps.

In order to move the apparatus in any desired direction in a regular manner when mounted on a barge or like floating support, we provide three spools 25 26 27, to which are fed the lines 2, 2^a, and 2^b, respectively. Each line is passed around its spool several times, 45 so that when the spool is rotated it frictionally takes up and gives out the line, thereby moving the barge. As shown in Fig. V, each spool is independently connected by suitable reversible gearing with the shaft of the drum 50 19, so that each spool may be operated independently of or simultaneously with the others to move either end of the barge or the entire barge as may be desired or to hold the barge 55 stationary as the work proceeds, the mechanism being so related and proportioned that when desired the barge may be moved a definite distance in any direction with each stroke 60

of the engine. By thus connecting the anchor-lines with the drum by which the excavator-lines are operated the location of the barge 65 may be shifted a definite determinate distance synchronously with the movement of the excavator, so that each load of the excavator may be taken with a definite determinate relation to the preceding load, which arrangement and synchronous operation is of 70 very great advantage in cleaning up bed-rock which is out of view under the water, and it is thence known that no portion of the bed-rock escapes the action of the excavator. This arrangement is also of very great advantage in 75 grading the bottom of rivers or other waterways, as by thus synchronously moving the barge and operating the excavator the successive cuts of the excavator will be made on 80 the same level, and the grade maintained, and the bottom not cut up with holes or left with hills and bumps.

While we have in the accompanying drawings illustrated our invention as applied to a 85 barge, it will be readily seen and understood that the primary features of our invention are entirely independent of the particular character of the support upon which they are mounted and operated. Hence we desire to 90 treat the floating barge herein illustrated in interpreting and construing the generic character and features of our invention simply as a convenient and typical form of platform or support upon which the apparatus embodying 95 such generic features of our invention is carried and operates. Certain minor and more specific features of our invention relate to the means for automatically advancing or otherwise moving the barge synchronously with 100 the operation of the excavator, and hence in such detailed and restricted contemplation of our invention the underlying support in the character of a floating barge constitutes a co-operating element of our invention bearing 105 an intimate relation to the excavator and its hoisting and swinging mechanism; but, as hereinabove stated, in its generic aspect the apparatus embodying our present invention is independent of any particular character of 110 support on which it is carried and operates, and hence we do not limit ourselves in the carrying out of our invention to its use on a barge, except in so far as the latter is made a coördinate and coöperating element of certain 115 of the claims hereinafter appended.

We claim as our invention—

1. In an apparatus of the character described, the combination with a suitable platform, of a boom swinging thereon on rockers, 120 an excavator suspended from said boom, and actuating devices for said excavator which by a continued movement first raise the excavator and subsequently move it, with the boom, in-

wardly over the platform in substantially the vertical plane of the boom's movement, substantially as and for the purposes described.

2. In an apparatus of the character described, the combination with a suitable platform of a boom swinging thereon on rockers, an excavator suspended from said boom, and hoisting-cables for said excavator passing over and in rear of said boom, which, by a continued pull first raise the excavator, and subsequently rock it with the boom inwardly over the platform in substantially the vertical plane of the boom's movement, substantially as and for the purposes described.

3. In an apparatus of the character described, the combination with a suitable platform and a receiving-hopper mounted thereon, of a boom having rocker-feet also mounted on the platform and so located thereon that its head may be rocked directly over the hopper, an excavator suspended from said boom by hoisting-cables which pass over the head of the boom, the parts being so relatively arranged and disposed that a continued pull on the hoisting-cables raises the excavator to the head of the boom and then swings both inwardly over the hopper in the vertical plane of the boom's rocking movement, substantially as described.

4. In an apparatus for raising and sluicing gravel from the beds of auriferous streams, the combination with a floating barge and a hopper and sluice-trough mounted thereon, of a rocking-boom also mounted on the barge and straddling the hopper, a hoisting-engine disposed on the barge in rear of the hopper, hoisting-cables passing from said engine over the head of the boom, and an excavator suspended by said cables, the excavator being raised and swung inwardly over the hopper by a single continued pull of the hoisting-cables which first raises the excavator and then rocks the boom, substantially as described.

5. In an apparatus of the character described, the combination with a rocking boom, a hoisting-cable running over the free end thereof, and an excavator suspended therefrom, of guides for the cable in rear of the boom and so placed as that the angle comprehended between the lines from the head of the boom to said guides and to the boom's point of support shall be slightly greater in all operative positions of the boom than the angle comprehended between the lines from the head of the boom to the excavator and to the boom's point of support, thereby minimizing shock when the excavator strikes the head of the boom and swings inwardly therewith, substantially as described.

6. In an apparatus of the character described, the combination with a suitable support, of a rocking boom carried thereon and provided with cable-guiding sheaves mounted in its head, a hoisting-drum, an excavator, a

hoisting-cable connecting said excavator with the hoisting-drum and passing over said guide-sheaves, and other guide-sheaves for the hoisting-cable located between the head of the boom and the hoisting-drum, and serving to maintain the cable at an angle with a line drawn from the head of the boom to its point of support which is constantly slightly greater than the angle comprehended between said last-named line and that portion of the cable by which the excavator is suspended from the boom, substantially as described.

7. In an apparatus for raising and sluicing auriferous sand, gravel and the like, the combination with a barge and a hopper and sluice-trough mounted thereon, of a rocking boom resting on said barge and straddling the hopper, said boom being provided with guide-sheaves in its head, a winding-drum and means for operating the same disposed in rear of the hopper, an excavator and a hoisting-cable therefor passing over said guide-sheaves and connected to said drum, whereby, when the drum is operated the excavator is first raised and subsequently swung inwardly with the boom and in the vertical plane of the boom's movement to discharging position over the hopper, and a pump arranged to discharge into the hopper at or near the bottom thereof, substantially as described.

8. In an apparatus for raising and sluicing auriferous gravel and the like, the combination with a barge of a rocking boom mounted thereon and carrying suitable guide-sheaves mounted in its head, an excavator, opening and closing cables passing over said sheaves for operating the excavator, mechanism for operating said cables to raise and lower the excavator, and mechanism driven by the same power that operates the excavator for effecting the travel of the barge proportionately to the work of the excavator, substantially as described.

9. In an apparatus for raising and sluicing auriferous gravel and the like, the combination with a barge and a rocking boom having suitable guide-sheaves mounted in its head and supported on said barge, and a gravel-receptacle also carried on the barge, of an excavator, opening and closing cables passing over said guide-sheaves for operating the excavator, means for operating said cables, spools mounted on the barge, and anchor-lines passing around said spools and connected with and operated by the means for operating the excavator-cables, whereby the travel of the barge is controlled synchronously and proportionately with the operation of the excavator, substantially as described.

10. In an apparatus for raising and sluicing auriferous gravel and the like, the combination with a barge, of a hopper and sluice-trough supported thereon, a rocking boom

mounted thereon and having its head adapted to rock rearwardly over the hopper, guide-sheaves mounted in the head of the boom, an excavator, a pair of operating-drums, opening and closing cables connecting the excavator with said drums respectively and passing over the guide-sheaves in the head of the boom, spools mounted upon the barge, suitable gearing intermediate said spools and the operating-drums, and anchor-lines passing around said spools in frictional engagement

therewith, and connected at their ends to suitable objects on the shore, whereby the travel of the barge is controlled synchronously and proportionately with the operation of the excavator, substantially as described. 15
